UNITED STATES PATENT OFFICE.

NATHAN AUGUST, JR., OF NEWARK, NEW JERSEY.

DESIGN FOR A COMBINED FAUCET AND WASTE FIXTURE.

Application filed March 16, 1927. Serial No. 21,152. Term of patent 14 years.

To all whom it may concern:

Be it known that I, NATHAN AUGUST, Jr., a citizen of the United States, and a resident of Newark, in the county of Essex and State of New Jersey, have invented a new, original, and ornamental Design for a Combined Faucet and Waste Fixture, of which the following is a specification, reference being had to the accompanying drawing, forming part thereof.

Figure 1 is a top plan view of a combined faucet and waste fixture showing my design, and

Figure 2 is a side elevation thereof.

I claim:

The ornamental design for a combined faucet and waste fixture as shown.
